UNITED STATES PATENT OFFICE.

GEORGE F. S. ZIMMERMAN AND HARRY ZIMMERMAN, OF FREDERICK, MARYLAND, ASSIGNORS OF ONE-THIRD TO CHARLES ZIMMERMAN, OF SAME PLACE.

DESIGN FOR A BRACKET FOR SHUTTER-BOWERS.

SPECIFICATION forming part of Design No. 25,129, dated February 4, 1896.

Application filed December 23, 1895. Serial No. 573,160. Term of patent 14 years.

To all whom it may concern:

Be it known that we, GEORGE F. S. ZIMMERMAN and HARRY ZIMMERMAN, citizens of the United States, and residents of Frederick, in the county of Frederick and State of Maryland, have invented a certain new and useful Design for Bell-Brackets for Shutter-Bowers; and we do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a representation of the design in perspective, and Fig. 2 is a face view of the same.

This invention has relation to a certain new and original design for bell-brackets for shutter-bowers; and it consists in the novel form and configuration thereof, all substantially as hereinafter described, and illustrated in the accompanying drawings.

The base portion of the bracket is of flat or plate form, with a symmetrical tail or extension *a*, the lateral edges of which are incurved, as shown at *b*. The inner portion of

this extension gradually widens from these curves and merges symmetrically into the 30 broader or body portion. The latter is provided with opposite projections or enlargements having convex edges and showing each a perforation. The tail or extension *a* also shows a perforation near its distant end. 35

Projecting from the broad or body portion of the base are two substantially parallel lug portions *c*, having convex outer faces and rounded ends *c*². Said portions *c* are connected near their outer ends by a rounded 40 portion *c*³. At the base of and between the said lug portions the bracket is open.

d is a raised rib or projection which is usually formed on the upper surface of the tail or extension *a*. 45

Having thus described our invention, what we claim is—

The design for a bracket for shutter-bowers substantially as herein shown and described.

In testimony whereof we affix our signatures in presence of two witnesses. 50

GEORGE F. S. ZIMMERMAN.

HARRY ZIMMERMAN.
